JEWEL MOUNTING

Samuel A. Hamin, Providence, R. I., assignor to
 Thomas McGrath, Inc., Providence, R. I., a
 corporation of Rhode Island

Application September 14, 1935, Serial No. 40,603

5 Claims. (Cl. 63—28)

The present invention relates to mountings for jewels, gems, brilliants, pearls or the like for ornamenting finger-rings, brooches, scarf-pins, ear-rings and other articles and objects and consists in improvements in mountings of the type disclosed in my prior patent, No. 1,818,324, issued August 11, 1931.

One of the objects of the present invention is to provide a mounting of the type indicated in which a ring of stones may be set and secured in place while the mounting is held in an upright position.

Another object of the invention is to provide a mounting of the type indicated including a pair of cooperating annular bezels forming a ring with a peripheral annular groove in which a cluster of stones are held.

Another object of the invention is to provide a mounting of the type indicated which is adapted to receive a central stone and an annular cluster of stones surrounding the central stone.

Another object of the invention is to provide a mounting of the type indicated having a highly ornamental appearance, a simple and compact structure lending to economical manufacture and assembly, and a sturdy construction for securely holding the stones in place.

Further objects of the improvement are set forth in the following specification which describes two embodiments of the invention, by way of example, as illustrated by the accompanying drawing. In the drawing:

Fig. 1 is a side elevational view of a finger-ring incorporating the jewel mounting forming the subject-matter of the present invention;

Fig. 2 is a plan view of the finger-ring illustrated in Fig. 1;

Fig. 3 is a sectional view of the mounting showing the cooperative relationship of its parts for holding a cluster of stones therein;

Fig. 4 is a detailed plan view of one of the bezels of the mounting showing the sockets in which the stones are set;

Fig. 5 is a perspective view of a modified form of mounting for an annular cluster of stones;

Fig. 6 is a perspective view of one bezel of the mounting shown in Fig. 5;

Fig. 7 is a perspective view of the opposite operating bezel of the mounting; and

Fig. 8 is a transverse sectional view of the modified form of mounting showing the location of the stones between the bezels and the manner of clamping the bezels in assembled relationship.

In the jewel mounting disclosed in my prior

patent, above referred to, the lower end of the inner bezel is flanged or swaged over to embrace the lower end of a depending flange on the outer bezel to hold the parts in assembled relationship. With this arrangement of the bezels it is necessary after the stones have been set to tip the mounting or turn it over to flange over the projecting end of the inner bezel. In turning the mounting over the stones are apt to fall out of place and when ornamenting a finger-ring the shank of the ring interferes with the insertion of the flanging tool. Still further, the application of a flanging tool to the end of the inner bezel tends to force the bezels apart rather than to draw them together in tightly assembled relationship.

The present invention corrects the above-mentioned deficiencies in a simple and compact arrangement of elements. In its broadest aspect the present invention provides a locking flange or collar which may be formed as a separate base member or integrally with one of the bezels. The collar extends upwardly through the central opening in one of the annular bezels and its end is flanged radially outward into engagement with the edge of this bezel adjacent the opening through which it extends to clamp the two bezels in assembled relationship. Due to the fact that the locking collar projects upwardly through the opening in the inner bezel its end may be deformed after the stones have been set, a flanging tool being applied through the open top of the inner bezel while the mounting is still in its upright position. Further, because of the shape and arrangement of the elements the flanging of the end of the collar tends to tighten the bezels rather than force them apart.

Referring first to Figs. 1 to 4 of the drawing, the numeral 10 designates the shank of a finger-ring which may be formed in one piece and rolled to provide an opening at the top to which an annular base-member of the mounting is soldered or otherwise suitably secured. As herein illustrated the base-member 11 is of generally trough-shape having an outer peripheral annular flange 12 to which the shank of the ring is soldered and a frusto-conical collar 13 extending upwardly at the center of the base. The sides of the finger-ring 10 adjacent the base-member 11 may be provided with suitable sockets 14 of usual construction for setting stones 15.

An annular bezel 16 is mounted on the base-member 11 with its outer edge seated against the peripheral flange 12 and with the frusto-conical

collar 13 extending upwardly through the relatively large central opening therein. The annular bezel 16, shown in detail in Fig. 4, is preferably stamped from a single piece of sheet material 5 and formed with a plurality of generally conical recesses or sockets 17 arranged in regular or any desired order around the central opening. The outer peripheral edge of the bezel 16 is bent to form an inwardly-extending flange 18, the flange 10 being ribbed to provide a series of curved shoulders 19 for engaging the beveled edges of a series 15 of jewels or stones 20 set in the sockets 17. The edge portion of the bezel 16 adjacent its inner periphery is curled over to form a depending annular flange 21, the edge of which seats against the frusto-conical collar 13 of the base-member 11. In the embodiment of the invention illustrated in Figs. 1 to 4 of the present drawing, the bezel 16 is of generally frusto-conical shape so 20 that stones 20 mounted therein face outwardly and upwardly, but it is to be understood that the bezel may be flat or take other contours.

An inner annular bezel 22 is mounted on the base-member 11 with the projecting collar 13 extending upwardly through its central opening. The inner bezel 22 has a conical portion 23 of the same general contour as the flange 21 of the outer bezel 16 to adapt it to seat thereagainst. Above the flange 21 the bezel 22 projects radially 30 outward to form an overhanging shoulder 24 overlying the sockets 17 in the bezel 16 to hold the stones 20 in place. The upper projecting end 25 of the collar 13 is flanged over into engagement with the inner peripheral edge of the inner bezel 22 to secure its conical portion 23 firmly seated against the flange 21 of the bezel 16. The lower end of the conical portion 23 is cupped or indented at 26 to receive the flanged end of the collar 13, the two connected parts thus 40 forming a continuous conical seat or socket for a central stone 27. The central stone 27 is held in its setting by the outer edge portion of the inner bezel 22 which is flanged over at 28 into gripping engagement with the peripheral edge 45 of the stone. Preferably, the upper edge of this flanged portion 28 of the inner bezel 22 is serrated to form a series of prongs 29 for gripping the edge of the stone 27.

In assembling the parts of the mounting the 50 annular base-member 11 may be soldered to the shank 10 of the finger-ring as explained above or when the mounting is to be used to ornament other articles the base-member is set in a suitable support. The outer bezel 16 is then placed over the conical collar 13 of the base-member 11 and seated on the annular flange 12. A series 55 of the stones 20 are then placed in the sockets 17 in the bezel 16 and are held on one side by the shoulders 19 on the outer periphery of the bezel which overlie one side of the sockets. The inner bezel 22 is then placed over the central collar 13 and pressed downwardly so that the annular horizontally-extending shoulder portion 24 engages the opposite sides of the stones 20 set in 60 the sockets 17 in the outer bezel member 16. Without changing the position of the mounting the bezels 16 and 22 are fastened together by inserting a suitable flanging tool through the opening in the inner bezel 22 to spread or swage 65 over the projecting portion 25 of the collar 13 into engagement with the conical portion 23 of the inner bezel member. As the force applied 70 at the end 25 of the base-member 11 is resisted by the shank 10 of the finger-ring or other support on which it is mounted there is no tendency

for the bezels to be separated during the flanging operation. Further, due to the frusto-conical contour of the collar 13 and the conical portion 23 of the inner bezel 22 which extends at an angle to the collar, the flanging of the end 5 25 tends to draw the two bezels tightly together.

The inner and outer bezel members 13 and 22 are thus securely fastened to the base-member 11 and the ring of stones 20 set between the bezels are securely held in place. The central stone 27 10 may be set in the seat formed by the conical portion 23 of the inner bezel 22 and the edge portion 28 of the bezel is deformed or flanged over into engagement with the peripheral edge of the stone to hold it in place. 15

A modified form of mounting is shown in Figs. 5 to 8 for an annular cluster of stones which may be used to ornament various articles. In this embodiment of the invention the base-member is eliminated and the locking means is formed integrally with one of the bezels. Each of the bezels 35 and 36 is in the form of an annulus of generally frusto-conical contour having a relatively large central opening. As shown in Fig. 6 the bezel 35 has its outer edge 37 serrated and 25 flanged over to provide a series of teeth or fine prongs extending around its entire periphery. The inner edge of the bezel 35 is also flanged inwardly to provide a laterally-projecting collar or rim 38 which has a function the same as the 30 frusto-conical collar 13 of the base-member 11 in the previously described modification. Between the inner collar 38 and outer flange 37 the bezel 35 has a series of recesses arranged at regular intervals to form sockets 39 for receiving a row of jewels or stones 40.

The opposite bezel 36, as shown in Fig. 7, has its outer peripheral edge 41 serrated and flanged inwardly and a central opening 42 of a diameter substantially the same as the outside diameter of 40 the laterally-projecting collar 38 on the opposite bezel 35. Recesses or sockets 43 are formed in the bezel 36 which cooperate with the sockets 39 in the bezel 35 to embrace the stones 40.

In this last-described form of construction the 45 bezel member 35 may be placed with its outer edge engaging a flat support so that the annular collar 38 extends upwardly. A series of the stones 40 are set in the sockets 39 around the bezel 35 to form a ring with their edges engaged by the 50 teeth on the serrated edge 37 of the bezel. The opposite bezel 36 is then placed over the bezel 35 with the collar 38 projecting upwardly through its central opening 42. The bezel 36 is then adjusted with respect to the bezel 35 so that the 55 sockets in the two bezels register and the edges of the stones are engaged by the serrated edge 41. The bezel 36 is pressed toward the bezel 35 and the projecting edge of the collar 38 on the bezel 35 is flanged over the inner edge of the bezel 36 to secure the parts of the mounting in assembled relationship as shown in Figs. 5 and 8. As in the 60 previously described construction the collar 38 may be flanged over while the bezel 35 is in such position as to retain the stones 40 in place so that 65 the operation of assembling the mounting is much simpler and convenient to perform. The ring of stones may then be mounted to ornament any suitable article such as a cylindrical container, pen or similar article or the mounting may 70 be used as a finger-ring.

The invention having now been described in detail it will be observed that a novel form of mounting is provided which facilitates the assembly of a cluster of stones for general use to ornament 75

ment articles of jewelry or embellish other objects. It will further be observed that the mounting provides a simple and compact structure having a highly ornamental appearance. It is also to be understood that the parts of the mounting may take other shapes and forms besides those disclosed herein without departing from the spirit or scope of the invention. Therefore, without limiting myself in this respect, I claim:

5 1. In a cluster setting for jewels, gems or the like, a frusto-conical supporting member having a flange at its base, an annular bezel mounted on the supporting member and engaging the flange, stone-receiving sockets in the bezel, a second 10 bezel cooperating with the first-mentioned bezel and having a shoulder overlying the sockets to engage and hold a plurality of stones set therebetween, and a flange at the opposite end of the frusto-conical member engaging the second-men- 15 tioned bezel to hold the bezels in assembled relationship.

20 2. In a mounting for jewelry, a pair of annular bezels cooperating to form a ring, sockets in one of the bezels for receiving a plurality of stones dis- 25 posed around its periphery, means on the bezels for engaging the stones to hold them in place in the sockets, means on one of the bezels for seat- 30 ing and gripping a central stone, and a base-member extending through the openings in the annular bezels and having flanges engaging the opposite sides of the bezels to hold them in as- 35 sembled relationship.

3. In a mounting for jewelry, inner and outer bezels cooperating to form a ring, said outer bezel having sockets for receiving a plurality of stones, a shoulder on the inner bezel overlying the sockets

to hold a plurality of stones therein, said inner bezel forming a socket for a central stone and having its outer edge flanged over to engage the stone, and a base member extending through the openings in both annular bezels and having flanges engaging the opposite sides of the bezels 5 to hold them in assembled relationship.

4. In a mounting for jewelry, an outer annular bezel having sockets for receiving a plurality of stones, means on the bezel for engaging one edge 10 of the stones, an inner bezel forming a socket for a central stone and having a shoulder overlying the sockets in the first-mentioned bezel to hold the plurality of stones therein, means on the inner bezel for gripping the central stone, and a 15 base-member extending through the openings in the annular bezels and having flanges engaging the opposite sides of the bezels to hold them in assembled relationship.

5. In a mounting for jewelry, a frusto-conical 20 base-member having a substantially right-angu- 25 lar flange extending from its base, an annular bezel mounted on the base-member and engag- 30 ing the flange at its base, said annular bezel hav- 35 ing sockets for receiving a plurality of stones, an annular bezel positioned within the first-men- tioned bezel and having a shoulder overlying the sockets thereof to hold the plurality of stones therein, said inner bezel forming a socket for a central stone, means at the outer periphery of the inner bezel for holding the central stone, and a flange at the upper end of the base-member for engaging the inner bezel to hold the two bezels in assembled relationship.

35 SAMUEL A. HAMIN.
